UNITED STATES PATENT OFFICE.

HOWARD W. MATTHEWS, OF LANSDALE, PENNSYLVANIA, ASSIGNOR TO DEXDALE HOSIERY MILLS, OF LANSDALE, PENNSYLVANIA, A CORPORATION OF PENNSYLVANIA.

KNITTING MACHINE.

Application filed July 7, 1926. Serial No. 120,911.

This invention relates to knitting machines, more particularly to the circular type ordinarily employed in the manufacture of seamless hosiery. The practice generally followed with such machines, is to produce the leg of the stocking by round and round knitting with all the needles in operation, and to provide the heel and toe portions through formation of pockets by widening and narrowing 10 upon a selected group of the needles (usually short butt needles) incidental to oscillation of the machine, while the remaining needles (long butt needles) are temporarily maintained idle or inactive.

15 The main object of my invention is to enable, through provision of automatic mechanism in machines with a single set of knitting cams, employment of any group of the needles separately for oscillatory knitting, as well as 20 transposal of the needle cylinder and the cams relatively so that the selected needle groups may be independently actuated by the knitting cams, thereby to produce, for example, heel tabs for the purposes of a knitting process such as set forth in U. S. Patent No. 924, 25 605 to Albet Gee, dated June 8, 1906; or again, by concurrent fashioning, to form complementary tapering toe tabs such as shown in U. S. Patent No. 388,678 granted to Samuel 30 Henshall, under date of August 28, 1888.

Other objects and attendant advantages will be readily apparent from the detailed description which follows in connection with the drawings; whereof Fig. I is a side elevation 35 of a circular stocking knitting machine conveniently embodying my invention.

Fig. II is a plan sectional view of the machine, taken as indicated by the arrows, II—II in Fig. I.

40 Fig. III is a longitudinal section, viewed in accordance with the arrows III—III in Fig. II.

Fig. IV is a transverse section taken, locally, as indicated by the arrows IV—IV in Figs. II and III.

45 Figs. V, VI and VII are diagrammatic detail views illustrating the operation of certain parts involved in my invention.

Fig. VIII is a partial plan view of the machine, with the needle cylinder removed.

50 Figs. IX and X are fragmentary detail sections, respectively taken as indicated by the arrows IX—IX and X—X in Fig. VIII.

Fig. XI is a diagrammatic illustration

showing a linear development of the knitting 55 cams and the needles.

Fig. XII is a perspective view showing the form of work which may be automatically produced as a result of the present improvements. 60

For convenience in delineation, I have herein shown my invention as embodied in a standard circular knitting machine of the type fully disclosed in U. S. Patents Nos. 1,266,044 dated May 1918, and 1,330,818 dated February 17, 1920, both granted to Albert M. Pigeon. With reference in detail to the drawings herewith, the needle cylinder designated 15 is rotatably supported upon an annular plate 16 at the top of a rod 17, which is guided in bearings 18 of the machine frame 19 for vertical shifting under governance of a rotary cam disc 20, in order to change the level of the needle cylinder 15 with respect to the knitting cams and thereby vary the size of the fabric loops. The cam disc 20 is secured to one end of a shaft 21, in the lower part of the machine frame 19, supporting the clutch drum 22, which, through a lever 23 and shift rod 24, controls the clutch by which the rotary and oscillatory phases of operation are determined. The mechanism involved in driving the machine under these two conditions of operation includes a pair of spur gears 25, 26 which are mounted on a common axis 27, and rotated by suitable intermeshing pinions on the main shaft 30 of the machine, the latter being equipped as shown in Fig. II, with tight, loose and medium speed pulleys 31, 32, 33 respectively. The main shaft 30 also carries a pinion 34 which receives oscillatory movement from a gear sector 35 having a crank link connection 36 with the spur gear 26, see Fig. III. During either mode 70 of operation, the motion received by the main drive shaft 30 is transmitted, through a pair of companion bevel gears 37, 38, to a spur gear 39 moving with the latter of said bevels. The spur gear 39, in turn, imparts the motion 75 to a gear 40 at the bottom of the needle cylinder 15 (Figs. II and III), all as described in the first of the two Pigeon patents hereinbefore referred to. Pawling of the ratchet teeth 22^a of clutch drum 22 (Fig. III) 80 is governed by the measuring chain 41 trained about a sprocket wheel 42 which is loose on the drum shaft 21, and adapted to be progressed anti-clockwise by action of a pawl 42,

70

upon an integrally-formed ratchet wheel 43, said pawl being reciprocated by virtue of pivotal coordination with the gear sector 35. The measure chain 41 has cam lugs 44, 45, which, in passing, successively engage a finger 46 to cause movement of a rock shaft 47. A second finger 48 on this rock shaft 47 imparts the movement to an arm 49 to effect retraction of an attached guard 50 from beneath the pawl 51 and allow the latter to pick the drum 22 clockwise for the purpose above stated.

As is usual with stocking knitting machines, the cylinder 15 is here equipped with a series of needles composed of two groups 52, 53, which, in the present instance, are equal as to number and respectively characterized by long and short butts distinguished by solid and light lines in Fig. XI. The instrumentalities for actuating the needles include a pair of stitch cams 54, 55, a bottom center cam 56, and side cams 57, 58, as well as a cam 59 for elevating the long butt needles 52 to the idle level in preparation for oscillatory knitting with the short butt needles 53 alone, and a depressing cam 60 whereby said long butt needles 52 are subsequently returned to the active level. The needle actuating means are further supplemented by raising pickers 61, 62, and drop pickers 63, 64 (Fig. VIII) for cooperation with said raising pickers alternately during widening incidental to the knitting of a heel pocket for example. The elevating and lowering cams 59, 60 (Fig. VIII) are respectively secured to levers 65, 66 which are pivoted intermediate their ends for independent swinging movement about a common fulcrum stud 67, and subject to leaf springs 68, 69. During rotary knitting, the elevating and lowering cams 59, 60 occupy the positions shown in the drawings; but concurrently with shifting of the clutch 22 in changing to the oscillatory phase of operation, their position is reversed, i. e., the elevating cam 59 is permitted to move inward under urging of its spring 68 while the depressing cam 60 is withdrawn. This action is brought about incidental to shifting of the clutch rod 24 to the left in Fig. VIII, said rod having attached to it a bracket 70 with inwardly extending fingers 71, 72 which engage studs 73, 74 respectively on the cam arms 65, 66 at opposite sides of their common pivot 67. The connections at 73, 74, it will be observed, allow independent movement of the cams 59, 60 as hereinafter more fully explained, in the former instance in opposition to an auxiliary bow spring 72^a. The bracket 70 also has a finger 75 that normally maintains the elevating picker 61 out of the way during round and round knitting.

In converting a knitting machine such as above briefly described to the purposes of my invention, provisions are made to enable circumferential shifting of the needle cylinder

15 relative to the driving means therefor so that the long butt needles 52 may be employed in lieu of, or in alternation with the short butt needles 53 for fashioning purposes. The means to this end include an auxiliary 70 clutch collar 76 that is slidable as well as free to rotate on the bearing sleeve 77 of the shaft 78, to the lower end of which the bevel gear 38 is secured, as shown in Fig. III. The collar 76 has a pair of depending pins 79 (in 75 the present instance diametrically arranged) engaging registering apertures in the gears 38, 39, and is urged downward, for normal maintenance of this engagement, by a helical compression spring 80 surrounding the bearing sleeve 77. The office of actuating the auxiliary clutch collar 76 is relegated to a yoke arm 81 secured to one extremity of a rock shaft 82 that is journaled in bearings projecting inward from the side 19^a of the 85 machine frame 19, see Figs. II, III and IV. To the opposite extremity of the rock shaft 82 is secured another arm 83 whose end lies within the cleved head 84 of a bolt 85 having bearing, with capacity for up and down 90 movement, in the boss 86 of a T shaped plate 87, see Fig. IV. This plate 87 rests on a transverse web 19^b of the machine frame 19, and is longitudinally slid able under guidance of screws 88 engaging slots near the ends 95 of its cross bar 87^a. The tongue 87^b of the plate 87 passes through an aperture in the side 19^c of the machine frame 19; and the protruding end thereof is given the form of a handle 87^c. A spring influenced latch 89 100 (Fig. I) pivoted at 90° to the side 19^c of the machine frame 19, normally engages behind a lug 91 on the protruding end of the plate tongue 87^b so as to hold the plate 87 in the position illustrated, in Figs. II and IV, in 105 opposition to the pull of a coiled spring 92. Tripping of the latch 89 is preferably given over to the measuring chain 41 for control, said chain being accordingly further equipped, as shown in Fig. III, with special lugs 93, 94 110 in a different plane from the lugs 44, 45 for engaging a finger 95 on a supplemental shaft 96. This shaft 96 extends outward through a bearing of the machine frame 19, to afford attachment for a lever 97 which is coupled, 115 by means of a link 98, with the latch 89. From Figs. III and IV, it will be noted that the bolt 85 carries, near its lower end, a side roller 99 designed to be acted upon by a cam 100 secured to the face of the spur gear 26 120 aforementioned. This roller 99, it will be seen, is held without the province of the cam 100, as shown in Fig. V; when the plate 87 is locked by the latch 89 in the normal position, illustrated in Fig. IV. However, when the latch 89 is tripped incidental to passage of one of the special lugs 93, 94, beneath the finger 95, the plate 87 is released to the action of its spring 92 and thereby drawn to the right (with respect to Fig. IV), thus 125 130

bringing the roller 99 in ⁵ the path of the cam 100, as shown in Fig. VI. When engagement takes place between the cam 100 and the roller 99, the bolt 85 is raised and such motion is transmitted to the rock shaft 82. As a consequence, the yoke arm 81 is swung upward to lift the auxiliary clutch collar 76 for withdrawal of the pins 79 on the latter from the bevel gear 38. The gear 39 and the ¹⁰ needle cylinder 15 are thus permitted to remain temporarily quiescent. For the purpose of restoring the plate 87 to the normal position immediately after the action just described, I mount on the gear 26 a second cam 15 101 with a laterally projecting edge adapted to engage a small axial roller 102 at the bottom of the bolt 85. When therefore such engagement takes place, as shown in Fig. VII, the plate 87 will obviously be shifted to the ²⁰ left in Fig. IV, to permit the latch 89 to automatically snap into place behind the lug 91 on said plate. The period during which the auxiliary clutch collar 76 is held raised, it will be seen, is but momentary, so that the ²⁵ pins 79 on said collar are caused to re-enter the bevel gear 38 upon completion of a half revolution of the latter and thus re-couple the spur gear 39.

In order to bring down the long butt ³⁰ needles 52 to the active level for fashioning I provide a special lowering cam 105 (see Figs. VIII to XI) which is secured to the inner end of a spring influenced rod 106 slideable in a bearing bracket 107, said rod being ³⁵ held from rotation by means of a pin 108 projecting through a guide slot in the bearing bracket 107. The special lowering cam 105 is controlled by a vertical slide 109 with a cam bevel 110 adapted to cooperate with a ⁴⁰ collar 111 on the protruding end of the rod 106. The slide 109 has guidance in the bed plate of the machine, as well as in a projecting bearing lug 112 of the annular plate 16, which rotatably supports the needle cylinder ⁴⁵ 15, and said rod is coupled, by means of a link rod 113, with the tail 114 of a finger 115 fulcrumed at 116 on the machine frame 19. The end of this finger 115 lies in the path of a laterally projecting screw stud 117 on the ⁵⁰ side face of the drum 22, see Fig. III, and, when engaged thereby, causes downward movement of the slide 109 in opposition to a spring 118, thereby allowing the lowering cam 105 to seek the inner dotted position shown in Fig. IX under urging of the spring ⁵⁵ to which it is subject.

As hereinbefore stated, during the oscillatory phases of operation, the cam 59 (Fig. VIII) is maintained in active position. Now ⁶⁰ it will be remembered that this cam 59 serves to elevate the long butt needles 52 and must therefore be withdrawn from action when fashioning is practiced, with said long butt needles in accordance with the present invention. For this purpose I provide a bolt 120,

(see Figs. VIII and X) with a chainfered upper end, adapted, when lifted, to swing the tail of the arm 65 inward thereby to retract the cam 59. When lifted, the bolt 120 is held raised by engagement of the tail of the arm ⁷⁰ 65 within an angular recess 120^a in the side of said bolt and thus temporarily locks the cam 59 in the inactive position. The bolt 120 may be actuated by any suitable means, for example, a lever 121 which is centrally ⁷⁵ fulcrumed at 122 to the side of the machine frame 19, and has its opposite end pivotally connected to the link 98, associated with the tripping mechanism for the latch 89.

The operation of the machine is as follows:—

Let it be assumed that the needle cylinder 15 has two hundred sixty needles, that the leg and heel pocket of the stocking are knitted in the usual way, and that the machine is ⁸⁵ just completing the last rounds of the foot portion immediately previous to change to the oscillatory phase of operation for fashioning the stocking toe. The latter operative phase is initiated by passage of the lug ⁹⁰ 44 of the measuring chain 41 beneath the finger 46 for progression of the drum 22 and shifting the main clutch of the machine. With incidental shifting of the clutch rod ⁹⁵ 24, the bracket 70 is moved to the left in Fig. VIII, which is attended by withdrawal of the cam 60 and placement of the cam 59 to active position for raising the long butt needles 52 constituting half the full complement to the idle level. With succeeding oscillation of the needle cylinder 15, the short butt needles 53 are raised by the pickers 61, 62, one at a time, until but a few, say fifteen, remain in action. When the narrowing has been carried out to the desired extent, the finger 115 is engaged ¹⁰⁰ by the screw stud 117 on the drum 22 (Fig. III) to be followed by inward movement of the special lowering cam 105 to intercept the long butt needles 52 and bring them all down to the active level. This period in the cycle ¹⁰⁵ is graphically represented in Fig. XI, from which it will be observed that the oscillating movement of the needle cylinder 15 is to the left and that the long butt needles 52 have just started down the incline of the special ¹¹⁰ lowering cam 105. Contemporaneous with these events, the special lug 93, on the measuring chain 41, engages the finger 95 thereby to effect tripping of the latch 89; and, through the interposed parts influenced as a ¹¹⁵ result thereof, projection of the roller 99 into the path of the cam 100, as shown in Fig. VI. Upon engagement of these two elements ¹²⁰ 99, 100, the auxiliary-clutch collar 76 is raised to uncouple the gear 39 from the companion bevel gear 38 with consequent change in the operative relation of the needle cylinder 15 with respect to the knitting cams. Concurrent with tripping of the latch 89, the bolt 120 is shifted upward to withdraw the cam ¹²⁵ 130.

59 (this being made possible by virtue of the notch in part 71, Fig. VIII, at the connection 73) and temporarily hold it retracted while narrowing proceeds in precisely the same manner as before but with the long butt needles 52 in action, the group of fifteen short butt needles 53^a (Fig. XI) previously left at the active level simply moving back and forth with the cylinder 15 at this time without entering the stitch drawing grooves formed by the knitting cams 54, 56 and 57, since the oscillatory throw of said cylinder 15 is actually less than a complete revolution.

At the end of the second fashioning operation, the cam lug 94 engages the finger 95 thereby tripping the latch 89 a second time and effecting another circumferential transposition of the needle cylinder 15 to restore it to the original normal operative relation with regard to the knitting cams 56, 57 and 58; while the lug 45 on the measuring chain 41, at the same time, engages the finger 46 to bring about restoration of the machine to the rotary phase of operation. As the bracket 25 70 is moved inward (to the right in Fig. VIII) during the last described period in the cycle, the finger 71, in re-engaging the stud 73, imparts slight excess movement to the lever 65 so that the bolt 120 is released to fall under influence of gravity to the normal position shown in Figs. I and X. It is also important to here note that the slotted connection at 74 in Fig. VIII permits premature shifting of the lowering cam 60 without inducing any harmful results since said cam is thus free to yield under action of the bow spring 72^a.

By operation of the machine as above described, it will be apparent that two complementary tapered selvage-edged flaps or tabs T-T are formed in continuation of the tubular foot portion F of the stocking, as shown in Fig. XIII. These tabs T, T may subsequently be united along the selvage edges by looping thereby to form a very neat and attractive toe.

Having thus described my invention, I claim:

1. The combination in a knitting machine comprising a needle cylinder, driving means including a gear for rotating and oscillating the cylinder, fashioning means to actuate the needles during oscillatory knitting, and pattern mechanism to control the fashioning means; of means to effect angular positional changes of the cylinder relative to the fashioning instrumentalities for the purpose of operation with different groups of the needles during oscillatory knitting, said means including a cylinder clutching means with a trip member adapted to be operatively engaged by cams on the gear aforesaid, and means subject to the pattern mechanism to move the trip member.

2. The combination in a knitting machine

comprising a needle cylinder, having means including a spur gear with associated companion gears for rotating and oscillating the cylinder, fashioning means to actuate the needles during oscillatory knitting, and pattern mechanism to control the fashioning means; of means to effect angular positional changes of the cylinder relative to the fashioning instrumentalities for the purpose of operation with different groups of the needles during oscillatory knitting, said means including a clutch normally coupling the companion gears but adapted to disconnect the same through a member engageable by cams on the spur gear aforesaid, a latch normally restraining said member from engagement by the gear cams, and means controlled by the pattern mechanism to trip the latch.

3. The combination in a knitting machine comprising a needle cylinder, driving means including a gear for rotating and oscillating the cylinder, fashioning means to actuate the needles during oscillatory knitting, and pattern mechanism to control the fashioning means; of means to effect angular positional changes of the cylinder relative to the fashioning instrumentalities for the purpose of operation with different groups of the needles during oscillatory knitting, said means including a cylinder clutch and co-ordinate trip mechanism with a member capable of axial motion in temporarily disconnecting the cylinder clutch and of lateral movement to restore clutching relation by co-operative engagement with cams on the gear aforesaid, and means subject to the pattern mechanism to release the trip mechanism.

4. The combination in a knitting machine comprising a needle cylinder, driving means including a gear for rotating and oscillating the cylinder, fashioning instrumentalities to actuate the needles during oscillatory knitting, and pattern mechanism to control said instrumentalities; of means to effect angular positional changes of the cylinder relative to the fashioning instrumentalities for the purpose of operation with different groups of the needles during oscillatory knitting, said means including a cylinder clutch and co-ordinate trip mechanism with a member having freely journaled rollers rotative in directions at right angles to one another and adapted for operative engagement by successive cams on the gear aforesaid to temporarily disconnect and restore clutching relation, and latching means subject to the pattern mechanism to release the trip mechanism.

5. The combination in a knitting machine comprising a needle cylinder, driving means including a gear for rotating and oscillating the cylinder, fashioning instrumentalities to actuate the needles during oscillatory knitting, and pattern mechanism to control said

fashioning instrumentalities; of means to effect angular positional changes of the cylinder relative to the fashioning instrumentalities for the purpose of operation with different groups of the needles during oscillatory knitting, said means including an auxiliary cylinder clutch and co-ordinate trip mechanism, a vertically movable element in said mechanism having bearing in a horizontally slideable member, freely rotative rollers at right angles to one another on the vertically movable element, individual cams on the gear aforesaid co-operative with the rotative rollers in temporarily disconnecting and restoring clutching relation respectively, and latching means engaging the slideable member controlled by the pattern mechanism to release the trip mechanism.

6. The combination in a knitting machine comprising a needle cylinder, driving means including a gear for rotating and oscillating the cylinder, fashioning instrumentalities to actuate the needles during oscillatory knitting, and pattern mechanism to control said fashioning instrumentalities; of means to effect angular positional changes of the cylinder relative to the fashioning instrumentalities for the purpose of operation with different groups of the needles during oscillatory knitting, said means including an auxiliary cylinder clutch and co-ordinate trip mechanism, a vertically movable bolt in said mechanism afforded bearing in a T-shaped spring-influenced horizontally-slideable member, rollers on the bolt rotative at right angles to one another, cams on the gear afore-

said co-operative with said rollers to respectively effect temporary disconnection and re-engagement of the cylinder clutch, and latching means adapted to the slideable member under control of the pattern mechanism to release the trip mechanism.

7. The combination in a knitting machine comprising a needle cylinder, driving means including a spur gear with associated companion gears for rotating and oscillating the cylinder, fashioning instrumentalities to actuate the needles during oscillatory knitting, and pattern mechanism to control said fashioning instrumentalities; of means to effect angular positional changes of the cylinder relative to the fashioning instrumentalities for the purpose of operation with different groups of the needles during oscillatory knitting, said means including an auxiliary cylinder clutch and co-ordinate trip mechanism, a vertically movable bolt in said mechanism afforded bearing in a T-shaped spring-influenced horizontally-slidable member, rollers on the bolt rotative at right angles to one another, cams on the spur gear aforesaid co-operative with said rollers to respectively effect temporary disconnection and re-engagement of the companion gears, and latching means adapted to the slidable member actuatable by the pattern mechanism to release the trip mechanism. 45 50 55 60 65

In testimony whereof, I have hereunto signed my name at Lansdale, Pennsylvania, this 30th day of June, 1926.

HOWARD W. MATTHEWS.
